Assistant Examiner — Brett Miller

(21) Appl. No.: **29/437,484**

(74) *Attorney, Agent, or Firm* — Underwood & Associates, LLC

(22) Filed: **Nov. 16, 2012**

CLAIM

(51) LOC (10) Cl. **13-02**

The ornamental design for a power supply bar for mobile audio systems, as shown and described.

(52) **U.S. Cl.**

DESCRIPTION

USPC **D13/110; D13/123**

(58) **Field of Classification Search**

USPC D13/107, 108, 123, 110, 118, 119;
320/108, 114, 164

See application file for complete search history.

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The three linearly-arranged cone frustums shown in dashed lines on the top of the power supply bar illustrate set-screw-type fastening devices that can be used to hold a conductive wire within the power supply bar and form no part of the claimed design.

FIGS. 6 & 7 are shown at a larger scale.
